STAND FOR HIGH CHAIRS

Benjamin Felsher, New York, N. Y.

Application September 4, 1945, Serial No. 614,099

14 Claims. (Cl. 155—149)

1

This invention relates to stands for high chairs. It is particularly directed to an improved stand which may be used in conjunction with the seat of a baby walker such as shown in my Patents No. 2,115,257, issued April 26, 1938, for Baby walker convertible into high chair, and No. 2,360,483, issued October 17, 1944, for Baby Walker convertible into high chair.

An object of this invention is to provide a stand of the character described which may be easily collapsed and which when so collapsed will stand upright.

Another object of this invention is to provide a stand of the character described comprising a front leg member, a bottom support pivoted to the lower end thereof and connected thereto by braces, and a seat pivoted to the upper end of the front leg member and braced in horizontal position, said bottom member being swingable upwardly toward the front leg members and the seat being swingable downwardly, and said stand being adapted to stand by itself in upright position when collapsed.

Yet a further object of this invention is to provide a stand of the character described to which the seat portion of a baby walker may be easily attached to form a high chair.

Yet another object of this invention is to provide a strong, compact and durable device of the character described which shall be easy to collapse and set up, which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a side elevational view of a stand embodying the invention in set up condition for use;

Fig. 2 is a rear view thereof;

Fig. 3 is a top plan view of the stand;

Fig. 4 is a side view of the stand in collapsed or folded condition;

Fig. 5 is a rear view of the stand in folded condition;

Fig. 6 is a cross-sectional view taken on line 6—6 of Fig. 1;

2

Fig. 7 is a cross-sectional view taken on line 7—7 of Fig. 3;

Fig. 8 is a side view of a high chair embodying the invention and illustrating a modified form of seat; and

Fig. 9 is a partial cross-sectional view similar to Fig. 6 but illustrating a modified construction.

Referring now in detail to the drawing, 10 designates a stand for a high chair embodying the invention. The same comprises a front leg member 11. Said front leg member comprises a pair of downwardly, forwardly and outwardly inclined, symmetrical legs 12. Said legs 12 are interconnected by a lower horizontal cross bar 13 and an upper horizontal cross bar 14. Attached to the lower ends of the legs 12 and extending rearwardly therefrom and disposed below bar 13 are angle brackets 15, each having an upwardly extending arm 15a riveted or otherwise fixed to the leg, and a rearwardly extending arm 15b disposed above the lower end of the leg.

Hinged to the rear ends of the arms 15b are aligned hinges 16. Attached to the hinge members 16 is a three-sided bottom support 17. The bottom support 17 comprises parallel side members 18 and a rear horizontal member 19. Member 19 may be attached to the rear ends of members 18 by means of angle brackets 20 and corner plates 21, or in any other suitable manner. Members 18 are attached to the hinges 16 by screws 22. The hinges 16 are spaced rearwardly of the forward ends 18a of members 18.

The hinges 16 are so spaced that when member 17 is swung upwardly to the position shown in Fig. 4, the lower ends 18a of members 18 will contact the floor to retain the folded stand in upright position.

It will thus be seen that the distance from arms 15b of brackets 15 to the lower ends of legs 12 is substantially similar to the distance from said arms of said brackets to the lower ends of members 18. The hinges 16 swing about horizontal axes 24. On each hinge plate 16 is a rearwardly extending hook 25 for the purpose hereinafter appearing.

Attached to the underside of the corners formed between members 18 and 19 are short projections 26 which serve as legs to engage the floor when the stand is set up. Attached to the outer side of each of the legs 12 is a headed pin 30 for the purpose hereinafter appearing. Rotatable on each member 18 is a collar or strap 31 carrying a horizontal pivot pin 32 above said member. Pivoted on each pivot pin 32 is a metal bar or brace member 34. At the upper end of

each brace member 34 is a notch 35 to engage one of the pins 30. The brace members 34 thus retain leg member 11 in set up condition.

It will now be understood that braces 34 may be disengaged from pins 30 and swung downwardly to horizontal position extending diagonally of member 17. Braces 34 thus cross each other and may engage within hooks 25.

Straps 31 rotate about members 18 but are retained against shifting lengthwise by screws or other projections 37 screwed into said member.

Means is provided to prevent brace 34 from accidentally becoming dislodged from engagement with pins 30. To this end there is mounted on each of members 12 above pins 30, brackets 38, each carrying a pivot pin 39 perpendicular to said leg member. Hinged on each pivot 39 is an angle plate 40 adapted to be swung downwardly into engagement with the outer edge of brace 34 as shown in Figs. 1 and 2 of the drawing. The angle plates 40 prevent the brace members from becoming accidentally dislodged. However, when the stand is to be collapsed, plates 40 can be swung forwardly to release the brace members.

For the purpose hereinafter appearing there is attached to the side of each of the brace members 34, a Z-shaped bracket 43 having an arm extending upwardly and spaced from the brace. Attached to each brace member is a pivot pin 45 extending inwardly thereof. Attached to each pivot pin 45 is a hook 46 for the purpose hereinafter appearing.

Hinged to the upper end of the leg member 11 is a seat support member 50 adapted to be assembled with the seat of a baby walker of the type shown in my Patents Nos. 2,115,257 and 2,360,483. To this end there is attached to the rear of the legs 12 adjacent their upper ends, hinge plates 51 each provided with a horizontal hinge pin 52. Hinged to each hinge pin 52 is a hinge plate 53. The hinge plates 53 are attached to the underside of seat support 50. Seat support 50 overlies the upper ends of the legs 12 and extends rearwardly therefrom. Said seat is formed with a notch 59a to receive a co-operating seat member similar to that shown in said patents and therefore not shown herein. Metal bars 54 may be attached to the side edges of seat support 50 and extend rearwardly therefrom. Said metal bars 54 may be of angular transverse cross-section being formed with inwardly extending horizontal flanges 55 on which the co-operating seat member disclosed in said patents may rest when assembled with seat support 50.

Means is provided to support the seat support 50 in horizontal position. To this end there is pivoted to each of the side bars 54 a brace 60. The braces 60 are formed with outwardly bulged portions 61 at their lower ends. Adjacent the lower ends of said portion 61 is a transverse metal bar 62 riveted to said braces. The metal rod 62 is adapted to contact the braces 34 and the lower ends of the braces 60 are adapted to engage within the brackets 43 thereby supporting the seat support 50 in horizontal position. The hooks 46 are adapted to engage the rod 62 to prevent the braces 60 from accidentally becoming disengaged with respect to the braces 34.

In Figs. 1, 2 and 3 the stand is shown, in set up position. In Figs. 4 and 5 the stand is shown collapsed. In order to collapse the stand, the hooks 46 are first disengaged. Braces 60 are pulled upwardly there being sufficient clearance between the upper portion of leg 12 and the over-

lying foreportion of the seat support 50 to permit the braces 60 to be moved upwardly just enough to clear the braces 34. The plates 40 are then swung outwardly to disengage the braces 34. Said braces are then disengaged from hooks 30 and laid down in crossing position on member 17 in engagement with the hooks 25. The seat 50 is allowed to hang and the braces 60 hang from the seat. Member 17 is swung upwardly. Preferably 10 the seat 50 when hanging contacts the outer side of member 17 so as to keep the latter from swinging downwardly again.

The stand 10 is provided with a foot rest 70. To this end there is fixed to the upper ends 15 of legs 12 inwardly extending screws 71. The screws 71 are screwed into opposite edges of a foot support plate 72. Attached to the lower end of plate 72 is a shelf or foot engaging plate 73. Pivoted to a side of plate 72 as at 74 is a brace 20 75 formed with notches 76. Said notches are adapted to engage pin 77 fixed to the leg 12 and extending inwardly therefrom. The brace 75 will thus support the foot rest in position for use. When the stand is to be collapsed, the brace 75 may be disengaged from the pin 70 and the foot rest will then swing down against member 11.

The seat support 50 may be replaced by any other suitable type of high chair seat which will 30 support a child, instead of being in the form of a seat adapted to receive the rear of a baby stroller such as shown in my above-mentioned patents.

In Fig. 8 there is shown a high chair 10a embodying the invention and comprising a stand similar to the stand 10. The seat support 50 however is replaced by a complete baby's high chair seat 80 which may be similar to the seat shown in my Patent No. 2,360,483. It may comprise a seat bottom 81, a back 82, side arms 83, a tray 84, and side walls 85. The chair 80 may either be collapsible or rigid as desired.

In Fig. 9 there is shown a modified construction. In Fig. 9 the bar 62 is omitted. Instead there 45 is attached to the inner side of each brace 60 a bracket 90. Interconnecting the lower end of brace 60 with bracket 90 is a horizontal rod 91 to be engaged by one of the hooks 46.

It will thus be seen that there is provided a 50 device in which the several objects of this invention are achieved, and which is well adapted to meet the conditions of practical use.

As various possible embodiments might be 55 made of the above invention, and as various changes might be made in the embodiment above set forth, it is to be understood that all matter herein set forth or shown in the accompanying drawing is to be interpreted as illustrative and not in a limiting sense.

Having thus described my invention, I claim 60 as new and desire to secure by Letters Patent:

1. A stand comprising a front leg member, brackets attached to said front leg member, a bottom member hinged to said brackets, braces 65 on said bottom member, means on said front leg member to engage said braces, a seat support pivoted to the upper end of said front leg member, and braces hinged to said seat and engaging the first-mentioned braces to support said seat in horizontal position.

2. A stand comprising a front leg member, a pair of brackets attached to the lower end of the front leg member and extending rearwardly therefrom, a bottom member hinged rearwardly 75 of its forward end to said brackets, the forward

end of said bottom member being adapted to contact the floor when said bottom member is swung upwardly about the hinges which connect said bottom member to said brackets, brace members interconnecting the rear of the bottom member with an upper portion of the front leg member, a seat pivoted adjacent its front end to the upper end of said front leg member, and brace means to support said seat in horizontal position.

3. A stand comprising a front leg member, a pair of brackets attached to the lower end of the front leg member and extending rearwardly therefrom, a bottom member hinged rearwardly of its forward end to said brackets, the forward end of said bottom member being adapted to contact the floor when said bottom member is swung upwardly about the hinges which connect said bottom member to said brackets, brace members interconnecting the rear of the bottom member with an upper portion of the front leg member, a seat support pivoted adjacent its front end to the upper end of said front leg member, and brace means to support said seat support in horizontal position, said last means comprising a brace means hinged to the seat support and engaging said brace members.

4. A stand comprising a front leg member, a pair of brackets attached to the lower end of the front leg member and extending rearwardly therefrom, a bottom member hinged rearwardly of its forward end to said brackets, the forward end of said bottom member being adapted to contact the floor when said bottom member is swung upwardly about the hinges which connect said bottom member to said brackets, brace members interconnecting the rear of the bottom member with an upper portion of the front leg member, a seat support pivoted adjacent its front end to the upper end of said front leg member, and brace means to support said seat support in horizontal position, said last means comprising a brace means hinged to the seat support and engaging said brace members, and means to prevent disengagement of said brace means from said brace members.

5. A stand comprising a front leg member, a pair of brackets attached to the lower end of the front leg member and extending rearwardly therefrom, a bottom member hinged rearwardly of its forward end to said brackets, the forward end of said bottom member being adapted to contact the floor when said bottom member is swung upwardly about the hinges which connect said bottom member to said brackets, brace members interconnecting the rear of the bottom member with an upper portion of the front leg member, a seat support pivoted adjacent its front end to the upper end of said front leg member, brace means to support said seat support in horizontal position, said last means comprising a brace means hinged to the seat support and engaging said brace members, means to prevent disengagement of said brace means from said brace members, and means to prevent disengagement of said brace members with respect to the front leg member.

6. In a high chair stand comprising a front leg member, a bottom member hinged adjacent its front end to said front leg member, straps rotatably and non-slidably mounted on said bottom member, braces hinged to said straps, pins on said front leg member, and means on said braces to engage said pins.

7. In a high chair stand comprising a front leg member, a bottom member hinged adjacent its

front end to said front leg member, straps rotatably and non-slidably mounted on said bottom member, braces hinged to said straps, pins on said front leg member, means on said braces to engage said pins, and means hinged to the front leg member and adapted to engage said braces to prevent the same from becoming disengaged from said pins.

8. A high chair stand comprising a front leg member, a bottom member hinged adjacent its front end to said front leg member, straps rotatably and non-slidably mounted on said bottom member, braces hinged to said straps, pins on said front leg member, means on said braces to engage said pins, and means hinged to the front leg member and adapted to engage said braces to prevent the same from becoming disengaged from said pins, a seat support pivoted to the upper end of the front leg member, a brace pivoted to said seat support, means on said first braces to engage the lower end of said seat support brace.

9. A high chair stand comprising a front leg member, a bottom member hinged adjacent its front end to said front leg member, straps rotatably and non-slidably mounted on said bottom member, braces hinged to said straps, pins on said front leg member, means on said braces to engage said pins, means hinged to the front leg member and adapted to engage said braces to prevent the same from becoming disengaged from said pins, a seat pivoted to the upper end of the front leg member, a brace pivoted to said seat, means on said first braces to engage the lower end of said seat brace, and hooks on the first braces adapted to engage the seat brace.

10. A stand comprising a front leg member, a bottom member hinged rearwardly of its forward end to the front leg member, said bottom member and front leg member having portions adapted to contact the floor when said bottom member is swung upwardly about its hinge members, means to brace said bottom member to said front leg member, a seat support member hinged at its forward end to the upper end of said front leg member, and means for supporting the seat support in horizontal position.

11. A stand comprising a front leg member, a bottom member hinged rearwardly of its forward end to the front leg member, said bottom member and front leg member having portions adapted to contact the floor when said bottom member is swung upwardly about its hinge members, means to brace said bottom member to said front leg member, a seat support member hinged at its forward end to the upper end of said front leg member, means for supporting the seat support in horizontal position, and means to retain said brace means in bracing position.

12. A stand comprising a front leg member, a bottom member hinged rearwardly of the forward end thereof to the front leg member, said bottom member and front leg member having portions adapted to contact the floor when said bottom member is swung upwardly about its hinge members, means to brace said bottom member to said front leg member, a seat support hinged at its forward end to the upper end of said front leg member, means for supporting the seat support in horizontal position, means to retain said brace means in bracing position, and leg means on said bottom member adapted to contact the floor when said bottom member is in horizontal position.

13. A stand comprising a front leg member, a bottom member hinged rearwardly of its forward

end to the front leg member, said bottom member and front leg member having portions adapted to contact the floor when said bottom member is swung upwardly about its hinge members, means to brace said bottom member to said front leg members, a seat member hinged at its forward end to the upper end of said front leg member, means for supporting the seat in horizontal position, means to retain said brace means in bracing position, and leg means on said bottom member adapted to contact the floor when said bottom member is in horizontal position, said brace means comprising a pair of braces hinged to a rotatable member on said bottom member and adapted to be moved to a position where they cross each other and lie against said bottom member.

14. A high chair comprising a front leg member, a bottom member hinged rearwardly of its forward end to the front leg member and extend-

ing rearwardly and adapted to contact the floor, braces interconnecting the bottom member with the front leg member, a baby's high chair seat pivoted to the front leg member and extending rearwardly therefrom, and brace means connecting said seat with said braces.

BENJAMIN FELSHER.
